UNITED STATES PATENT OFFICE.

WILLIAM C. KRAUSE, OF MILWAUKEE, WISCONSIN.

BOX-PROTECTOR.

1,384,391.

Specification of Letters Patent. Patented July 12, 1921.

Application filed November 22, 1920. Serial No. 425,749.

To all whom it may concern:

Be it known that I, WILLIAM C. KRAUSE, a citizen of the United States, and resident of Milwaukee, in the county of Milwaukee and 5 State of Wisconsin, have invented certain new and useful Improvements in Box-Protectors; and I do hereby declare that the following is a full, clear, and exact description thereof.

10 My invention refers to skeleton containers or bottle crates, rectangular in form and having wooden side and end walls, the same being of that general type such as is disclosed in Patent No. 933184, dated September 7th, 1909. Crates of this general character are adapted to travel or slide upon conveyers and the bottom edges thereof, are subjected to severe wear, which causes quick 15 deterioration, and thereby renders the 20 crates, otherwise in good condition, impractical for use.

My present invention has for its object to provide means for preventing the wear upon the bottoms of such crates, incidental 25 to their uses as stated above. Specific objects of the invention are:

To provide the lower side wall edges with metallic shoes or runners whereby said edges are protected;

30 To provide grooves in the edges of the side wall for the reception of metallic runners, whereby they will be held in position with relation to the side walls, but will project below the bottom edge to thus eliminate 35 wear;

To provide such runners in the form of wire strands, partly embedded in the bottom edges of the crate side walls, having upturned ends at acute angles and fitted in 40 corresponding sockets, whereby the runners are held in position under more or less spring tension.

With the above and other minor objects in view, the invention consists in certain 45 peculiarities of construction and combination of parts as are hereinafter set forth with reference to the accompanying drawings.

In the drawings:

50 Figure 1 represents a fragmentary view of a crate, partly in section, having attached thereto a metallic shoe or runner embodying the features of my invention.

Fig. 2 is an inverted plan view of the 55 same, and

Fig. 3 is a cross section through one of

the side walls showing the runner embedded therein.

Referring by characters to the drawings, A—A represents wooden panel end walls of 60 a rectangular crate, having side walls B—B. The end and side walls in this instance are reinforced by corner irons C, which corner irons form no part of my invention. The box-like crate, so constructed, is provided 65 with the usual skeleton structure (not shown) to support bottles or other articles adapted to be fitted therein. The bottom edges of the side panels B are provided with longitudinal grooves 1, into which grooves 70 are fitted wire strands 2, preferably round in cross section, the same constituting runners. The wire strands, as best shown in Fig. 3, are of such cross sectional area with respect to their grooves that the lower edges 75 of said strands project below the bottom edges of the panels, so as to form protecting runners therefor.

As best shown in Fig. 1, the longitudinal grooves 1 extend approximately throughout 80 the length of the panels B, and at the ends these grooves are intersected by upwardly extending sockets 3, which sockets are disposed at acute angles to the groove. The ends of the runners are turned upwardly to 85 form anchor legs 4, which legs are sprung into the sockets, and owing to the fact that they are slightly compressed when inserted, the expansive force of the legs will tend to hold the runners rigidly in their assembled 90 relation with the panels. *

In some instances, as shown in the exemplification of my invention, the corner irons C may be provided with outwardly extended flanges c—c', which flanges overlap the 95 bottom edges of the juxtaposed side and end panels. The flanges c, in this case, may be arranged to fold over the end portions 4' of the runners, whereby they are positively secured in their nested position with relation to their panel grooves. Obviously, crates equipped with these runners will be 100 protected against wear, due to their hard usage, and the life of such crates is materially extended. It will also be observed 105 that owing to the simple arrangement whereby the runners are attached, that crates equipped with them can be manufactured at a minimum cost, which is a material factor in marketing an article of this 110 character.

While I have shown and described certain

specific arrangements for retaining the runners, obviously changes can be made in the attaching means, within the scope of the skilled mechanic without departing from the 5 spirit of my invention.

I claim:

1. A rectangular crate of the character described, having wooden side and end panels, the bottom edges of the side panels being provided with longitudinal grooves, metallic runners fitted in the grooves adapted to project above the bottom surface of the panels, and means for securing the ends of the runners to said panels.
- 10 2. A rectangular crate of the character described having wooden side and end panels, the bottom edges of the end panels being provided with longitudinal grooves terminating with upwardly extending sockets, disposed at acute angles to the grooves, and metallic runners partially embedded into the grooves having upturned ends nested in the sockets under tension.
- 15 20

3. A rectangular crate of the character described having wooden side and end panels, the bottom edges of the end panels being provided with longitudinal grooves, the grooves terminating with upturned sockets and metallic runners partially embedded into the grooves having upturned ends fitted into the sockets.

4. A rectangular crate of the character described having wooden side and end panels, the bottom edges of the end panels being provided with longitudinal grooves terminating with upturned extended sockets, metallic runners partially embedded into the grooves having upturned ends fitted in the sockets, and corner irons for the panels having flanges overlapping the ends of 40 the runners.

In testimony that I claim the foregoing I have hereunto set my hand at Milwaukee, in the county of Milwaukee and State of Wisconsin.

WILLIAM C. KRAUSE.
